UNITED STATES PATENT OFFICE.

JOSIAH S. ALBRIGHT, OF VAN WERT, OHIO, ASSIGNOR OF ONE-HALF TO
CHARLES E. LAWHEAD, OF SAME PLACE.

PUMP.

SPECIFICATION forming part of Letters Patent No. 651,688, dated June 12, 1900.

Application filed March 24, 1900. Serial No. 10,049. (No model.)

To all whom it may concern:

Be it known that I, JOSIAH S. ALBRIGHT, a citizen of the United States of America, residing at Van Wert, in the county of Van Wert and State of Ohio, have invented new and useful Improvements in Pumps, of which the following is a specification.

One object of this invention is to provide an improved pump by which the water is lifted and discharged from the spout through the medium of an auxiliary air-pump which is connected to the main pump-cylinder, the said air-pump lifting the water into the main pump-cylinder upon the upstroke of the piston and discharging the water upon the downstroke of said piston.

A further object of the invention is to provide a peculiar construction of pump-valves by means of which the water is permitted to leak past the valves when the latter are at rest, so that the water will readily drain from the body of the pump and prevent freezing.

With the above objects in view the invention consists in the peculiar construction and combination of parts comprising the pump, all as will be hereinafter fully set forth, and specifically pointed out in the appended claims.

In the accompanying drawings, which form a part of this specification, and in which like letters of reference indicate similar parts throughout the several views, Figure 1 is a side elevation of a pump constructed in accordance with my invention. Fig. 2 is a vertical sectional view through the pump. Fig. 3 is an enlarged detail view of one of the pump-valves.

Referring to said drawings, A designates the main pump-cylinder, which is provided at its ends with flanges *a a*, to which are bolted a top plate B and the flanged upper end *c* of the well-pipe C. At one side of the cylinder A is formed an outlet pipe or elbow D, the upper end of which is provided with a flange *d*, to which is bolted a cylinder or valve casing E, and to the upper end of this cylinder or valve casing is bolted the discharge-pipe or pump-stock F, terminating in a spout G. In the lower ends of the cylinders A and E are located ball-valves H and I, respectively, the movement of said balls off their seats being limited by means of webs *s*, formed in the

cylinders, said webs also directing the balls onto their seats and insuring the passage of the water around said balls. The seats of the ball-valves are of peculiar construction for the purposes of the invention, and as they are similar a description of one will apply to both. Said improved valve-seat is made up of a bent plate K, the upper member *k* being narrower than the lower member *k'* and lies normally above the same to permit water to pass around said upper member and through the opening in the lower member for the purpose hereinafter explained. The member *k* of the seat is also adapted to close down upon the lower member to form a tight valve during the operation of pumping, and though both members are provided with central openings for the passage of the water when the ball is off its seat the said ball is adapted to fit into the opening of the upper member. The said valve-seats are held in place as shown in the accompanying drawings.

L designates the air-pump, which is located in the rear of the pump-stock F and is bolted to a bracket M, projecting therefrom. The cylinder of the air-pump is connected to the upper end of the main pump-cylinder A by a vertical pipe N, which is a comparatively small pipe, and working in the cylinder of the air-pump is a piston O, connected by a rod P to a lever or pump-handle R, the latter being pivoted at its inner end to ears *t* of a two-part collar T, bolted on the pump-stock. The inner end of the lever or handle is bifurcated to embrace the pump-stock and bring the pivot-point in front of said pump-stock, so that the desired movement can be imparted to the piston of the air-pump without requiring an excessive movement of the operating end of said lever or handle.

In the operation of the pump the upstroke of the piston of the air-pump draws the water into the main cylinder A, past the ball-valve H, and upon the downstroke of said piston the valve H closes and the water is forced past the valve I and into the discharge-pipe, it being understood that the valve I closes upon the upstroke of the piston to prevent back pressure in the discharge-pipe. It will also be noted that during the operation of the pump the pressure upon the ball-valves

quickly closes the member *k* of the valve-seat upon the member *k'*, and thereby prevents any leakage around the valves. When the pump is at rest, however, the members 5 *k* of the valve-seats, being relieved of pressure, will rise slightly and permit the water to leak through the valves, and thereby drain the body of the pump. This is particularly desirable in winter, as it will drain all the 10 water from the exposed parts of the pump and prevent freezing. The water drains from the discharge-pipe and cylinder A, and therefore in starting the pump the air is forced out of said cylinder and discharge-pipe as the water is being lifted.

15 The pump herein shown and described is simple in construction, can be put up at small expense, and by having the air-pump or operating mechanism located as shown it is not affected by the water and can be readily examined or repaired in case it should get out of order. The particular construction and arrangement of the valves also insures their 20 perfect operation while the pump is in use, forming tight valves, while they also provide 25 for draining the pump when it is at rest.

Having thus described my invention, what I claim as new, and desire to secure by Letters Patent, is—

30 1. In a pump, the combination, of the cylinders A and E connected to each other and to the well-pipe and discharge-pipe, respectively, ball-valves located in the bottom of said cylinders and closing downward, and 35 valve-seats for the balls comprising a spring-plate bent upon itself to form two parts nor-

mally separated, said parts having pening through the upper part; together with an air-pump connected to one of the cylinders, and means 40 for operating said air-pump, substantially as shown and for the purpose set forth.

2. A ball-valve for a pump, comprising, in combination with the ball, a plate bent upon itself to present two parts normally separated 45 and provided with openings, the ball being adapted to close one of the openings, substantially as shown, and for the purpose set forth.

3. In a pump, the combination, of the cylinders A and E connected to each other and to the well-pipe and discharge-pipe, respectively, ball-valves located in the bottom of said cylinders and closing downward, and valve-seats for the balls comprising a bent 50 plate presenting two parts normally separated; together with an air-pump supported adjoining the pump-stock, a collar attached to the pump-stock and having ears located on the opposite side of said pump-stock from 55 the air-pump, and a pump-handle having a bifurcated lever pivoted to the aforesaid ears, the pump-handle being connected to the piston-rod of the air-pump, substantially as shown and described.

60 In testimony whereof I affix my signature in presence of two witnesses.

JOSIAH S. ALBRIGHT.
